(57) **CLAIM**

I claim the ornamental design for an adjustable slider track for mounting wall panels unto a sidetrack attached to an existing wall, as shown and described.

DESCRIPTION

FIG. 1 is a perspective view of the adjustable slider track for mounting wall panels unto a sidetrack attached to an existing wall, showing front, left and bottom sides in accordance with the present design;

FIG. 2 is a left elevational view thereof;

FIG. 3 is a bottom plan view thereof;

FIG. 4 is a top plan view thereof;

FIG. 5 is a front devotional view thereof;

FIG. 6 is a back devotional view thereof; and,

FIG. 7 is a right devotional view thereof.
